J. HALL

PROPELLED BATHING DEVICE

Filed Nov. 7, 1927

FIG. 1

FIG. 2

FIG. 3

INVENTOR
Judson Hall

By Charles R. Wells Atty

UNITED STATES PATENT OFFICE.

JUDSON HALL, OF HARTLAND, WISCONSIN, ASSIGNOR OF ONE-FOURTH TO BENJAMIN F. BAYHA AND ONE-FOURTH TO HERBERT A. BELL, BOTH OF MILWAUKEE, WISCONSIN.

PROPELLED BATHING DEVICE.

Application filed November 7, 1927 Serial No. 231,407.

This invention relates to improvements in a propelled bathing device, and more particularly to a self-propelled device adapted to carry or pull a body or bodies over the surface of the water.

The invention contemplates more especially the provision of a new and novel self-propelled device highly desirable for use in bathing or water sports, and which may be put to many other and varied uses as will be apparent to one skilled in the art.

Many and varied devices adaptable for water sports have been heretofore known but in most instances these devices were not self-propelled, but were made to be towed by water craft or actuated directly by the user. Moreover, in most cases, these devices were designed especially to retain all of the larger portion of the user's body out of the water. In the use of former water sport devices actuated by towing or the like, the direct control of the device was in the hands of the tower, and the user or rider of the device had no way of directly controlling the maneuvers of the same.

With the above noted defects and objections in view, the present invention is designed to provide a new, novel, and buoyant craft highly desirable for use in bathing and water sports, wherein the user has full and complete control of the device at all times.

The invention also seeks to provide a new and novel pontoon device adapted to permit the attachment thereto of a portable driving element.

Another object of the present invention is to provide a device of the character described adapted to draw a user's body directly through the water.

A further object of this invention is to provide a device which is safe at all times and capable of adequately supporting a body or bodies even when the device is not in motion.

While some of the more salient features and characteristics of a device embodying this invention have been above pointed out others will become apparent from the following disclosures.

The invention includes these and other features of construction and combinations of parts hereinafter described and shown in a preferred form in the drawings, as more particularly indicated by the claims.

In the drawings:

Figure 1 is a side view in elevation of a device embodying principles of the present invention, showing the same in operative position.

Figure 2 is a top plan view of the device in operative position.

Figure 3 is a vertical sectional view, with parts omitted and parts in elevation, taken substantially along the line III—III of Figure 2.

As shown in the drawings:

In the illustrated embodiment of this invention there is shown a pair of spaced buoyant members or pontoons 1 and 2, respectively. These pontoons are more or less of a boat-shaped form to aid them in more efficiently traveling through the water. Connecting the pontoons 1 and 2 and rigidly maintaining the same in spaced relationship is a beam or yoke 3, an end of which is attached to each pontoon adjacent the mid-portion thereof.

The yoke 3 is constructed of any desired material, but preferably of a floatable material. It is to be noted that this yoke extends upwardly and forwardly, thereby providing an arcuate forward under surface 4 and a sloping upper portion 5 at the rear thereof for purposes that will later appear. A substantially horizontal forward face 6 is left upon the upper surface of the yoke 3. The face 6 is recessed as at 7 preferably adjacent the mid portion thereof to provide a substantially narrow shelf 8.

The shelf 8 provides a suitable seat for a driving element 9 which, in this instance, is shown as an outboard motor of standard construction. Secured to the motor 9 or to the beam 3, if desired, in any suitable manner, is a cross-bar or handle 10 which is grasped by the user of the device. If so desired, the handle, of course, may be removably mounted, thereby permitting the use of a standard outboard motor.

In using the present invention the user or rider grasps the handle 10 as indicated by the dotted lines in Figures 1 and 2, the motor having been started. The motor, therefore, will pull the device through the water and the user's body will be towed directly through the water. It is to be noted that the handle is disposed in close relationship to the motor whereby the user may properly control the motor with one hand at any and all times. When traveling through the water the arcu-

ate under surface 4 on the beam 3 tends to eliminate unnecessary impedance due to waves, rough water, or the like. The sloping rear portion 5 effectively shields the anterior portion 6 of the user's body from the irritating effects of rough water.

It has been found desirable to lock the steering control of the motor so that the device would travel in a straight line. The user 10 may then turn or maneuver the device at will by using his body as a rudder. Of course, if so desired, the motor rudder 11 may be utilized for steering purposes, and if such is the case, it is preferable to reverse the rudder 15 as shown in the drawings, since with the present device a standard motor would be pulling instead of pushing. The standard motor would obviously have to be driven in reverse gear to acquire the pulling action, 20 but it is readily apparent that a motor may easily be designed or a standard motor converted into a type that will normally be a puller.

It is to be noted in conjunction with the 25 handle 10, that adjacent the point on the right side thereof where the hand of the operator will grasp the same, there is mounted a spring contact button or lever 12. When grasped by the rider's hand, the button 12 30 will close the circuit through the wires 14 by contacting with any desirable form of contact disposed as indicated at 13. The wires 14 may be connected in the magneto circuit, so that if the circuit is broken between 35 contacts 12 and 13 by the rider's releasing his grasp upon the handle and permitting the contact 12 to spring away from the contact 13, the motor will stop. Obviously, in place of the contact shown herein any simple control mechanism may be substituted such as 40 speed control, controls to vary the pitch of the propeller blades, etc.

To permit the rider to safely remove both hands from the handle 10, a safety belt 15 is 45 provided which may embrace the rider's mid-portion and is preferably secured to the yoke 5 as shown at 16. Upon the sterns of the pontoons 1 and 2, handles 17 are provided to permit the device to accommodate several 50 riders at one time. The pontoons may also be provided with safety belts similar to the belt 15, if so desired. It is to be understood that riders may also be carried directly upon the pontoons 1 and 2, or that small boats may 55 be substituted therefor without departing from the spirit and scope of the present invention.

From the foregoing it is apparent that I have provided a novel device adapted to be 60 self-propelled or towed as desired, which is safe, easy to manipulate and which when self-propelled enables the user to have full

control thereover. Moreover, the device described herein is strong, durable, efficient in its action, and may be economically manufactured. 65

I am aware that many changes may be made and numerous details of construction may be varied through a wide range without departing from the principles of this invention and I, therefore, do not purpose limiting the patent granted hereon otherwise than necessitated by the prior art. 70

I claim as my invention:

1. In a device of the class described, a pair 75 of buoyant members, means connecting said members, a handle associated with said means, a handle mounted upon each of said members, said handles being graspable by users of said device so that said users will be towed thereby lying directly in the liquid floating said device, and means on said device for imparting motion thereto.

2. In a device of the class described, a pair 80 of pontoons, a yoke connecting the same, driving means for said device, a handle on said yoke, and means on said handle graspable by the user of said device, said means being operable therefor when released to stop the forward motion of said driving 85 means.

3. In a device of the character described, a pair of spaced pontoons, a yoke connecting said pontoons, integral means on said yoke for mounting a driving element thereon, 90 means to be grasped by a user of said device so as to be towed thereby, and means to retain said user connected to said device in the event the grasp of said user is released.

4. In a device of the character described, 100 a pair of spaced pontoons, a yoke connecting said pontoons, integral means on said yoke for the mounting of a driving element thereon, a handle to be grasped by a user of said device, and means on said handle for controlling said driving element and also graspable by said user, said means being operable 105 to stop said driving element when the grasp of said user is released.

5. In combination, a buoyant unit, propulsive means mounted thereon, means on said unit graspable by a user in such a manner that said user will be towed behind said unit in the liquid floating the same, means graspable by said user and operable when released to stop said propulsive means, and means for retaining said user connected to said element when the grasp of said user is released. 110

In testimony whereof I have hereunto subscribed my name at Hartland, Waukesha County, Wisconsin. 115

JUDSON HALL.
